UNITED STATES PATENT OFFICE.

FREDERICK W. BOBBITT, OF HOUSTON, TEXAS.

SWINGING CRIB.

1,176,811.

Specification of Letters Patent.

Patented Mar. 28, 1916.

Application filed March 11, 1915. Serial No. 13,820.

To all whom it may concern:

Be it known that I, FREDERICK W. BOBBITT, a citizen of the United States, residing at Houston, in the county of Harris and 5 State of Texas, have invented certain new and useful Improvements in Swinging Cribs, of which the following is a specification.

This invention relates to new and useful 10 improvements in a swinging crib.

The object of the invention is to provide a device of the character described adapted to be suspended from any suitable support and which is convertible into either a swinging 15 crib or a swinging seat and is designed particularly for the use of small children.

With the above and other objects in view the invention has particular relation to certain novel features of construction, arrangement of parts and use, an example of which 20 is given in this specification and illustrated in the accompanying drawings, wherein:

Figure 1 shows a plan view of the device when used as a swing. Fig. 2, shows the 25 device expanded and in position to be converted into a crib. Fig. 3 shows a sectional side view thereof, when used as a swing. Fig. 4, shows a sectional view of the side members taken on the line —a—a of Fig. 1. Fig. 5, shows an isometric view of the crib 30 frame. Fig. 6 shows a side view of the crib. Fig. 7 shows an end view of the swing, and, Fig. 8, shows an enlarged fragmentary view of the crib frame as attached to the swing.

Referring now more particularly to the drawings, the numerals 9, 9, designate the side members, and the numerals 10, 10, the side members, respectively, of the front and rear portions of the swing, said side members 35 being connected at their front and rear ends, respectively, by the front and rear cross bars 11, and 12. The inner ends of the side members 9, 9, are also connected by the cross brace 13. The seat 14, is suspended from this swing frame by means of the front strap 15, the side straps 16, 16, and the rear straps 17, 17, said straps being flexible. All these straps are secured to the seat, underneath, at their inner ends and 40 their outer ends are secured to the brace 13, the side members 9, 9, and the rear cross bar 12, respectively, and the straps 17, 17, 17, are further strengthened and held in position by the cross strap 18, having its ends

secured to the respective members 10, 10, 55 and to which the straps 17, 17, 17, are secured and these straps 17, 17, 17, and 18, form a back rest when the device is employed as a swing.

The under sides of the inner ends of the 60 members 9, 9, have lengthwise grooves, as 19, and are faced with plates, as 20, each having a lengthwise slot, as 21, cut therethrough and narrower than the corresponding groove, and secured to the upper sides 65 of the inner ends of the respective side members 10, 10, are screws, as 22, which project through the corresponding slots and have enlarged heads as 23, and the side members are thus slidably connected together. The 70 side members 9, 9, are braced relative to the brace 13, and also the side members 10, 10, are braced relative to the bar 12, by the braces 24, 24, and 25, 25, respectively, which are substantially triangular and secured, 75 respectively, to the members which they brace together.

The crib frame, shown in Figs. 5 and 6, has the corner posts 26, 26, 26, 26, and the side and end slots 27, 27, and 28, 28, whose 80 ends are secured to the respective corner posts and suitably braced relative thereto. When it is desired to convert the device from a swing into a crib, the respective side members 9, 9, and 10, 10, are pulled apart, 85 so as to lengthen the swing frame and the lower ends of said corner posts are then inserted into the corresponding brackets 29, 29, 29, 29, carried by the respective ends of the swing frame, and studs 30, 30, 30, 30, 90 project from said posts, which rest against the upper sides of the bars 11 and 12, and support the posts in said brackets.

The respective ends of the bars 11 and 12, have eyes 31, 31, 31, 31, secured thereto to 95 which the lower ends of the respective chains 32, 32, 32, 32, are attached, and the other ends of these chains are secured to the cross rod 33, which is suspended by means of the chain 34, having a resilient link 35. 100

When the device is used as a crib, as shown in Fig. 6, a pillow may be placed upon the seat 14, so as to make it adaptable for that purpose.

While I have shown only one form of the 105 device it is obvious that the structure thereof may be changed without departing from the principle of the invention and I hereby

reserve the right to make such changes as will not depart from the scope of the appended claims.

What I claim is:

5. 1. A device of the character described including an adjustable frame work, a seat and flexible straps suspending the seat from the frame work.
- 10 2. A device of the character described including a lengthwise adjustable swing frame, a seat suspended therefrom by means of flexible straps and a detachable crib frame mounted thereon.
- 15 3. A swinging frame formed of side and end members, the side members being formed of sections slidably united together, a seat, flexible straps by means of which the

seat is suspended, a crib frame mounted on said swing frame, and detachable therefrom and yieldable means suspending said device. 20

4. A swinging frame formed of side and end members, the side members being formed of sections adjustably connected so that the frame may be lengthened or shortened, a seat, flexible straps by means of 25 which the seat is suspended, said straps forming a back and sides for the seat.

In testimony whereof I have signed my name to this specification in the presence of two subscribing witnesses.

FREDERICK W. BOBBITT.
